UNITED STATES PATENT OFFICE.

LEE OZER GARRAWAY, OF MEMPHIS, TENNESSEE.

FOLDING STEP-LADDER.

1,108,896.

Specification of Letters Patent.

Patented Sept. 1, 1914.

Application filed December 1, 1913. Serial No. 804,087.

To all whom it may concern:

Be it known that I, LEE O. GARRAWAY, citizen of the United States, residing at Memphis, in the county of Shelby and State 5 of Tennessee, have invented certain new and useful Improvements in Folding Step-Ladders, of which the following is a specification.

This invention relates to folding step ladders, and has for one of its objects to improve the construction and increase the efficiency and utility of devices of this character.

Another object of the invention is to provide a device of this character having an improved construction of the frame and of the steps whereby the parts mutually embrace and reinforce each other so that the stability and steadiness of the device is increased, and displacement of the parts prevented when in use.

With these and other objects in view the invention consists of certain novel features of construction as hereinafter shown and described and then specifically pointed out in the claims, and in the drawings illustrative of the preferred embodiment of the invention.

Figure 1 is a perspective view of the improved device from the rear and in open position. Fig. 2 is a perspective view of one of the foldable steps detached. Fig. 3 is a perspective view, from the front, of the improved device in folded position. Fig. 35 4 is a front elevation in open position. Fig. 5 is a detail view of a portion of the device partly in section. Fig. 6 is a perspective view from above of the combined upper step platform and locking member. Fig. 7 is a perspective view from beneath of a modified form of the step. Fig. 8 is a view similar to Fig. 3 illustrating another modification in the construction of the step.

Corresponding and like parts are referred to in the following description and indicated in all the views of the drawings by the same reference characters.

The improved ladder comprises in general side members spaced apart, steps each 50 formed of two members hingedly united at their confronting ends and hingedly united to the sides to dispose into substantially parallel relations when the ladder is folded, a top step swinging from one of the side 55 members and adapted to engage the other

side members and hold the same distended, and brace members hingedly united to the sides and foldable together therewith.

The sides of the latter are precisely alike except that one is right and the other left-handed, and the description of one will suffice for both. 60

The ladder sides are each formed of longitudinal members spaced apart and represented conventionally at 11-12. Each longitudinal member is formed in L-shape and connected at the upper ends by a web 13 and at the lower ends by a web 14, while a transverse web 15 connects the longitudinal members opposite each step. Any required number of the steps may be employed but for the purpose of illustration two of the steps are shown, but it will be obvious that the ladder may be increased in length to any required extent with the 75 number of the steps corresponding to the length of the sides. Each of the webs 15 is formed with an inwardly directed upper portion 16 which extends between the sides 11-12 and forms a stop for the steps, as 80 hereafter explained. The members 11-12, the webs 13-14-15 together with the inwardly directed stops 16 are preferably formed from a single plate of metal and with the free edges turned over to increase 85 the strength. One of the webs 13 is provided with a slot 17, the object to be hereafter explained. Connecting the sides at the points where the steps are located are rods 18. 90

Pivoted at 19 to the side members 11 are swinging legs 20 each being preferably formed from an L bar with a cleft in the upper end of each, the material which is released by the cleft being bent over upon the 95 webs which constitute the legs as shown at 20'-20" to reinforce the legs, and the pivot 19 passes through one web of the legs and the turned over portion 20', and likewise through the member 12 near its upper part. 100 By this means the leg members 20 are free to swing toward or away from the sides, and by being pivoted transversely will fold closely against the sides when not in use, or projected rearwardly to support the sides 105 in inclined position, as hereafter explained. Pivoted at 21 to the rear webs of each leg member 20 are diagonal braces 22-23, the brace member 22 being provided with a longitudinal slot 24, while the brace member 110

23 is provided with a similar longitudinal slot 25.

The brace members 22—23 are arranged to cross each other intermediate the ends 5 with the slot 24 slidably engaging over a pin 26 projecting from one of the leg members 20, while the slot 25 of the brace member 23 engages over a pin 27 projecting from the other leg member. The pin 26 is threaded and provided with a wing nut 28, while the pin 27 is threaded and provided with a similar wing nut 29. By this means the brace members 22—23 may be clamped in position relative to the leg members 20 either 15 in closed or distended position, and firmly support them and preventing the collapsing of the device. The slot is located near the upper edges of the webs 13 and is utilized as a pintle upon which the upper step of the 20 ladder is mounted to swing. The upper step is represented in perspective in Fig. 4 and comprises a body portion 30 having a longitudinally directed enlargement 31 whereby a longitudinally directed opening 32 is produced, the inner wall of the enlargement 31 extending obliquely to the longitudinal plane of the body 30, so that the opening 31 tapers toward one side edge of the body. The 25 body portion 30 and the enlargement 31 are preferably constructed from a single plate of metal with the enlargement 31 riveted or otherwise secured at 33 to the body. Previous to riveting the portions 30—31 together the lower side of the enlargement is pivoted 30 through the slot, whereby the body 30 with its enlargement is free to swing upon the portion of the web 13 above the slot, as will be obvious.

The end of the body 30 opposite the enlargement 31 is reduced and bent into a hook-like form 34 to bear over the upper edge of the web 13 of the opposite ladder side, as shown. By this simple means the step 30 will perform the two-fold function 40 of a step and of a means for holding the sides of a ladder structure in spaced relations. At its rear edge the body 30 of the upper step is formed with an upwardly directed web 35 with its ends in relatively 45 close proximity to the inner edges of the rear webs of the members 11 of the sides, the upper edge of the web 35 the upper face of the enlargement 31 and the upper end of the hook-like portion 34 being in substantial 50 alignment when the ladder is in open and operative position. As shown the enlargement 31 and the hook-like terminal 34 of the upper step are of considerable height so that 55 when the step is connected to the sides of the ladder the body 30 will be located at a considerable distance below the upper ends of the ladder sides as shown in Fig. 1, whereby a shallow receptacle is produced closed at the ends and rear and portions of the front, 60 which will be found very convenient for

supporting pails, brushes, tools or other articles which may be employed in connection with the step ladder.

Attached to the rear face of the web 35 is an extension 36 having an upwardly opening 70 hollow 37 intermediate its ends, the device being so constructed that when the ladder is disposed in folded position the inner face of the body 30 will bear against the outer faces of the ladder side with which it is swingingly united, while the slot 37 of the extension 36 will engage over the adjacent pin 26, so that when the wing nut 28 is turned home the upper step will be firmly locked in folded position. The extension 36 likewise 80 serves as an extension to the back of the upper step to increase the depth of the receptacle before mentioned.

Each step of the ladder is formed in coacting sections hingedly united at their 85 confronting ends and swingingly coupled to the ladder sides. Each step comprises base portions 38—39 hingedly united at their confronting ends as represented at 40, the outer ends of the plates extending obliquely 90 to the longitudinal plane of the plate, so that when the latter sides are distended and disposed in their inclined position the outer ends of the plates will bear squarely against the inner faces of the outer webs of the 95 members 11—12.

The members 38—39, as before stated, are of metal, and bearing upon each plate 38 is a step or tread 41, while a similar tread 42 bears upon the plate 39. The members 100 41—42 are preferably of wood or similar material, and secured by screws or other suitable fastening devices to the members 38—39.

Depending from the members 38—39 near 105 their outer ends are U-shaped members 43—44 which engage over the rods 18 which extend through the front and rear webs of the members 11—12. Each of the step members 38—41 is supported upon one of the rods 110 18, while the step members 39—42 are each supported upon another of the rods 18 when in distended or operative position with the outer ends of the step members bearing 115 against the inner faces of the webs 15 and the adjacent portions of the side members 11—12. The webs 15, as before stated, are formed with inwardly directed upper portions 16, and the parts are so arranged that the inwardly directed portions 16 bear over the adjacent ends of the step members 38—39 when the latter are disposed in their horizontal or operative position and thus materially assist in holding the parts together 120 and preventing the sagging of the steps. The hinges 40 are located at the lower sides of the plates 38—39, and the confronting ends of the treads 41—42 bear against each other at a considerable distance above the 125 pintles of the hinges 40, and thus effectually 130

prevent all sagging of the steps below the horizontal line. The pintles of the hinges 40 are coupled by a stay member 47, the latter having a longitudinal slot 48 where it engages with one of the hinge pintles, preferably the upper one as shown, to provide a slight vertical movement or play between the parts to avoid cramping.

When the ladder is to be folded the wing nuts 28—29 are released, the hook-like member 34 of the upper step detached and the upper step swung upwardly and outwardly and into position substantially in parallel relation to the adjacent side of the ladder. The steps are then forcibly "buckled" upwardly and the ladder sides moved toward each other. This movement will cause the brace members 22—23 to move inwardly, the slots 24—25 permitting this movement. When the ladder sides and the buckled steps are drawn together the slot 37 of the upper step will be engaged with the adjacent pin 26 and the wing nut 28 turned home thus locking the upper step in position and likewise coacting with the wing nut 29 to firmly lock the parts in closed position. When the device is to be distended the wing nuts are released and the ladder sides drawn apart which will cause the step members to assume their operative position in longitudinal alignment. The upper step is then disposed in position with the hook-like terminal 34 engaged over the upper web 13, as shown in Fig. 1. The leg members 20 are then moved into rearward position and the wing nuts tightened up to hold the parts in locked relation.

In Fig. 7 a modification in the construction of the step is shown. In the modified structure the outer ends of the plates 38—39 are extended upwardly, thence outwardly as shown at 49 and thence downwardly and outwardly as shown at 50, the portion 50 being in longitudinal alignment with the plates 38—39 and spaced from the ends of the members 38—39. The inner ends of the portions 49 are extended obliquely to the longitudinal plane of the members 38—39, and the space between the extensions 50 and the outer terminals of the plates 38—39 are connected by rods 51 which perform substantially the same function as the U-shaped members 43—44, the rods 18 passing between the portion 49 and the pins 51, while the extensions 50 project beneath the inwardly directed portions 16 of the webs 15. The operation of the structure shown in Fig. 7 is substantially the same as that shown in Fig. 3, and may be employed under certain conditions.

In Fig. 8 another modification of the construction is shown consisting in bending the outer terminals of the members 38—39 downwardly as represented at 52 and thence outwardly as represented at 53, the portions 53

extending in the same longitudinal plane as the portions 38—39. L-shaped loops 54 are connected between the members 38—39 and the vertical extensions 52, and are designed to bear over the rods 18, and thus perform the same function as the members 43—44, as shown in Fig. 3 and as the pins 51 shown in Fig. 7, while the extensions 53 perform the same function as the extension 50 of the structure shown in Fig. 7 and bear beneath the inwardly directed portion 16 of the webs 15.

The rods 18 extend obliquely to the longitudinal plane of the ladder sides, so that when the ladder is disposed in open position with the sides inclined as shown in Fig. 1, the rods will be in horizontal position, and to enable the pivotally united step sections to engage closely between the channeled sides when the ladder is folded the loops 43 and 44 at the rear of the steps are longer than the loops 43 and 54 at the front of the steps. For the same reason the rods at the rear of steps, as in Fig. 7, are longer than the rods at the front of the steps.

One end of each of the loops 43 and 44 extends through both the members 38—39 and 41—42 and are riveted or headed at their upper ends against the treads. The other ends of the loops extend above the hinged members 38 and 39 so that the outer ends of the treads 43 and 44 bear against these extended portions. By this means the tread portions of the steps are firmly supported and reinforced and prevented from outward movement when strain is applied.

Having thus described the invention, what is claimed as new is:

1. In a step ladder, sides spaced apart and each formed of a longitudinally extending channel member with inverted U-shaped clefs in the body portion at the points where the steps are to be located and bent inwardly to form stops, a rod disposed between the webs of the side members adjacent to each stop, and steps each formed of coacting sections hingedly united at their confronting ends and swingingly engaging said rods, the outer ends of the step sections extending beneath the stops when the steps are distended.

2. In a step ladder, sides spaced apart and each including longitudinally extending members having inwardly directed stops where the steps are located, a rod extending between the longitudinal members adjacent to each stop, steps each formed of coacting members hingedly united at their confronting ends and bearing upon said rods with their outer ends beneath said stops, and holding members connected to said steps and bearing beneath said rods and arranged to permit the step members to move longitudinally thereof.

3. In a step ladder, sides spaced apart and

each including longitudinally extending members having inwardly directed stops where the steps are located, steps each formed of coacting members hingedly united 5 at their confronting ends with their outer ends beneath said stops, means for pivoting said steps respectively to said longitudinally extending members, and holding members connected to said steps and engaging said 10 pivots to permit the step members to move longitudinally thereof.

4. In a step ladder, sides spaced apart, a plurality of foldable intermediate steps swingingly united to said sides, legs swing- 15 ing from said sides, obliquely directed braces uniting said legs, clamp members adjustably connecting said braces to said legs, a com- bined platform and upper step swinging at one end from one of said spaced sides and 20 detachably engaging the other spaced side, said combined platform and upper step having a vertical flange at its rear edge, and an L-shaped member engaging said flange and the adjacent portion of the platform and 25 having an open slot for engaging the adjacent clamp member of the legs.

5. In a step ladder, sides spaced apart, a plurality of foldable intermediate steps swingingly united to said sides, legs each 30 formed of an L member having a cleft at the upper end and the portions of the leg released by the cleft bent over to reinforce the webs of the leg, pivot pins extending through one of said bent-over portions and 35 adjacent portion of the leg and pivotally engaging the sides and the other reinforcing portions of the leg bearing against the rear

face of the ladder sides when the legs are in open position and limiting the outward movement thereof. 40

6. In a step ladder, sides spaced apart and each including longitudinally extending members having inwardly directed stops where the steps are located, a rod extending between the longitudinal members adjacent 45 to each stop, steps each formed of coacting members hingedly united at their confronting ends and bearing upon said rods with their outer ends beneath said stops, treads bearing upon said coacting step sections and 50 abutting at their confronting ends, holding members extending at their inner ends through said coacting step sections and through said treads and extending at their outer ends against the outer ends of said 55 treads, said holding members adapted to engage said rods.

7. In a step ladder, coacting sides spaced apart, rods connecting said sides, coacting step sections hingedly united, treads secured 60 to said step sections and abutting at their confronting ends, holding members extending at their inner ends through said coacting step sections and through said treads and extending at their outer ends against the 65 outer ends of said treads, said holding members adapted to engage said rods.

In testimony whereof I affix my signature in presence of two witnesses.

LEE OZER GARRAWAY. [L.S.]
